UNITED STATES PATENT OFFICE

152,722

DESIGN FOR A WATER COOLER

Samuel O. Morrison, Pine Ridge, Pa.

Application September 29, 1947, Serial No. 141,636

Term of patent 14 years

(Cl. D67—4)

To all whom it may concern:

Be it known that I, Samuel O. Morrison, a citizen of the United States, residing at Pine Ridge, in the county of Delaware and Commonwealth of Pennsylvania, have invented a new, original, and ornamental Design for Water Coolers, of which the following is a specification, reference being had to the accompanying drawings, forming part thereof.

Figure 1 is a front elevation of a water cooler, showing my new design.

Figure 2 is a right side elevation of Figure 1.

The other side not shown is substantially like the side shown and the rear and top portions are substantially plain.

The dominant features of the design reside in the portions shown in full lines.

I claim:

The ornamental design for a water cooler, as shown and described.

SAMUEL O. MORRISON.
